UNITED STATES PATENT OFFICE.

JULIUS GIESECKE AND HERMANN GIESECKE, OF LEIPZIG-LEUTZSCH, GERMANY.

APPARATUS FOR FEEDING PAPER SHEETS.

Application filed April 5, 1927, Serial No. 181,087, and in Germany January 15, 1926.

This invention relates to an apparatus for feeding paper sheets, of that type in which a plurality of endless roll-guided conveyor ribbons are arranged in superposed fashion, 5 and it consists in that the single conveyor ribbons form inclined planes by the employment of roll pairs of different diameter, while the paper sheets thereon are supplied from one conveyor ribbon to the next one 10 and thereby turned over several times, the conveyor ribbons being commonly moved by an endless chain in such a way that the conveyor ribbon parts in contact with one another are equi-directed and of equal speed. 15 Beneath the upper part of the upper conveyor ribbon, and beneath the upper part of the lower conveyor ribbon, as well as between the upper part of the upper conveyor ribbon and the suction-rod of the suction 20 contrivance, a table plate is arranged. The suction-rod is driven by means of cog-wheel sectors. The advance of the ratchet-wheel of the contact device of known type is transmitted to the conveyor ribbons in a way corresponding to the removal of the paper 25 sheets from the apparatus.

The accompanying drawings illustrate the improved feeding apparatus by way of example:

30 Figs. 1 and 2 are respectively a side view and a front view of the same, and

Fig. 3 is a vertical section on the line A—B of Fig. 1, while

Figs. 4 to 7 show details of the apparatus.

35 The improved apparatus comprises two lateral frame parts 1 having angular slots 2 therein in which engage the trunnions of the suction-rod 3 of the suction contrivance. The driving-levers 4 of the latter are fulcrumed on bolts 5 and joined to the suction-rod 3 by means of links 6. On the ends of the driving-shaft 7 for the suction-rod movement, cog-wheel sectors 8 are keyed, of which the teeth are adapted to coact with cog-wheel sectors 9 keyed on a shaft 10. Crank-pins 11 fixed on the cog-wheel sectors 9 are connected by rods 12 with the levers 4. During the rotation of the cog-wheel sectors one tooth of the cog-wheel sectors 8 strikes 45 against one tooth of the cog-wheel sectors 9 whereby the latter receive a partial movement and are then stopped until they are moved farther by the next tooth of the cog-wheel sectors 8. By a suitable determination 50 of the width of the teeth and choice of the number of the latter, it is possible to ex-

actly determine the periods for the movements and for the stoppings of the levers 4. During the rotation of the cog-wheel sectors 8, 9 the levers 4 are reciprocated. By the 60 cog-wheel sectors 8, 9 the advantage is attained that the suction-rod driving-gear is not subjected to such a strong wear as are the hitherto used driving-gears comprising eccentrics. The improved driving-gear is 65 thus particularly adapted for use in connection with high-speed machines, for instance rubber printing machines.

Both ends of the driving-shaft 7 are further fitted with discs 13 having crank-pins 70 14 attached to the connection-rods of the air pumps.

In the two lateral frame parts 1, further, a roll 16 is revolvably mounted and connected by an endless conveyor ribbon 17 with a roll 18 of smaller diameter, of which the shaft 31 is also revolvably mounted in the frame parts 1. Below the upper part of the conveyor ribbon 17 a table plate 19 is fixed so as to extend between the two rolls 16 and 18, said table plate having a metal extension 20 projecting to the bar 21 over which the paper sheet is brought by the suction-rod 3 to the conveyor roll 23 by which the paper sheet is further conveyed.

85 In the frame parts 1, further, rolls 24 and 25 of different diameters are revolvably mounted, which are connected by a second conveyor ribbon 26 and so arranged that the lower part of the conveyor ribbon 17 90 runs parallel to the upper part of the conveyor ribbon 26. Below the conveyor ribbon 26 runs a third conveyor ribbon 27 located around rolls 28 and 29 of different diameters revolvably mounted in the frame parts 1. The conveyor ribbon 27 has a position declined to the right. Beneath the upper part of the conveyor ribbon 27 a table plate 30 is fixed. The paper sheets are placed on the table plate 30 in weakly 100 straightened condition and are during their conveyance over the multiple rolls further straightened, so that the table plate 30 need not be so long as with paper sheet feeding apparatus of known types. The three conveyor ribbons 17, 26, 27 are driven from the shaft 31 carrying chain-wheels 32 at its ends. Other chain-wheels 33 and 34 are keyed on the trunnions of the rolls 25 and 28. The three chain-wheels 32, 33, 34 are 105 so connected by means of an endless chain 35 that the trunnion of the roll 25 rotates

in clockwise direction, while the trunnions of the rolls 18 and 28 rotate in counter-clockwise direction. To this end, the chain is led over a loose chain-wheel that is adjustably mounted for attaining the required tension of the chain.

The paper sheets placed in straightened condition on the table plate 30 are caused to travel along with the upper part of the conveyor ribbon 27 until they come in contact with the second conveyor ribbon 26 by which they are further conveyed while running between the equi-directed parts of the conveyor ribbons 26 and 17 to the roll 16 where they travel upon the upper part of the conveyor ribbon 17 and pass onto the table plates 19 and 20. The paper sheets arrive thus at the suction contrivance in the same position as they are placed on the table plate 30 below. The lifting of the paper sheets is effected from above. The conveyor ribbons conveying the paper sheet piles are, at the places where they are almost in contact with one another, equi-directed and adapted to yield corresponding to the thickness of the piles. The rolls 16 and 25 are embraced by guiding rakes 38 and 39 adjustably mounted on bolts 37 and adapted to press the paper sheets upon the rolls.

The apparatus is fitted with a contact device of known type. The contact bars 40 are keyed on an axle 41, on which a lever 43 carrying a roller 42 as well as a lever 44 are fixed. The lifting of the roller 42 and thus of the contact bars 40 is effected, like that of the suction-rod 3, by means of the cam-disc 13.

The lever 44 is pivotally connected with a rod 45 (Figs. 4 and 5) of which the other end is connected with the short arm of a knee-lever 46, which is turnable on the bolt 47 and of which the long arm has an elongated slot 53. This slot is engaged by a pin 54 mounted on a slidable square rod 55 of which one end carries a plate 56. An axle 48 (Figs. 1, 5 to 7) carries a ratchet wheel 49 and a loosely turnable pawl-lever 57 on which a pawl 22 is slidably located and held by a springy bolt 58 of which the pointed end engages in one of the two notches 59 in the pawl 22. The latter carries further a pin 60. The reciprocation of the pawl-lever 57 can, for instance, be effected by the reciprocating driving-lever 4 (Fig. 1) which by a connection-rod is connected with a downwardly directed arm (not illustrated) of the pawl-lever 57. Or, the driving-lever 4 may be extended in upward direction and connected by a connection-rod with the pawl-lever 57 shown, or any other construction of known type may be provided for the reciprocation of the pawl-lever 57.

When removing the pile of paper sheets lying on the table plates 19, 20, also the con-

tact bars 40 drop, whereby the lever 44 is lifted and the knee-lever 46 turns in the direction of arrow (Fig. 4). Thereby, also the square rod 55 is displaced in the direction of arrow and the plate 56 is moved into the path of the pin 60 on the pawl 22, which pin is, during its oscillatory movements together with lever 57, moved downwards by the incline of the plate 56, so that the pawl 22 is forced into the teeth of the ratchet-wheel 49 and the latter is advanced during the further turning of the lever 57. During the return movements of the lever 57 the pin 60 with the pawl 22 is always moved out of the teeth of the ratchet-wheel 49 by the incline of a stationary plate 61 provided for this purpose. The pawl 22 remains then under the influence of the springy bolt 58 in the upper position and slips freely over the ratchet-wheel 49 if the plate 56 is retracted.

The axle 48 of the ratchet-wheel 49 carries a toothed wheel 50 meshing with a spur wheel 51 on the shaft 31. The advance of the ratchet-wheel 49 is transmitted by the toothed gearing 50, 51 to the shaft 31. By the rotation of the latter and by means of the endless chain, the rolls 32, 28, 25 and thus the conveyor ribbons are moved corresponding to the removal of the paper sheets from the apparatus.

The shaft 52 of the roll 29 may be fitted with a hand crank in order to bring at the beginning of the operation the paper sheets onto the suction contrivance by a corresponding initial movement of the conveyor ribbons 27, 26, 17.

The operation of the apparatus is briefly as follows: The paper sheets laid in straightened condition upon the lower table plate 30 are conveyed by means of the conveying ribbons 27, 26, 17 onto the upper table plates 19 and 20, lifted by the suction contrivance, and led to the conveyor roll 23. When removing the paper sheet pile from the table 19, the contact bars thereon are lowered and cause by the contact device described (Figs. 4 to 7) the further conveyance of the fresh paper sheets placed on the table plate below.

The paper sheets piles are blown from the front as well as from the rear, and that by means of the existing pump, that is double-acting.

What we claim is:—

1. In an apparatus for feeding paper sheets, the combination of a suction contrivance comprising a suction-rod, a plurality of endless conveyor ribbons arranged in superposed fashion, roll pairs of different diameters guiding said ribbons and locating them like inclined planes, an endless chain to commonly move said ribbons in such a way that the ribbon parts in contact with one another are equi-directed and of equal speed, and a plurality of table plates, one ar-

ranged below the upper part of the upper conveyor ribbon, another one below the upper part of the lower conveyor ribbon, and a third one between the upper part of the upper conveyor ribbon and said suction-rod, said latter table plate forming an extension of the first-mentioned table plate.

2. In a construction as specified in claim 1, a driving shaft, cog-wheel sectors keyed thereon, other revolvably mounted cog-wheel sectors adapted to come in gear with the first-mentioned cog-wheel sectors, crank-pins fixed on said revolvably mounted cog-wheel sectors, oscillatory driving-levers, connection-rods between the latter and said crank-pins, and links joining said levers with said suction-rod.

3. In a construction as specified in claim

1, a contact device comprising contact bars arranged above the table plate between the upper part of the upper conveyor ribbon and the suction-rod, a ratchet wheel, an axle for the latter, a pawl-lever for said ratchet wheel influenced by said contact bars, a toothed wheel on said ratchet wheel axle, and a spur wheel on one of the trunnions of said conveyor ribbon rolls in gear with said toothed wheel and adapted to transmit the advance of said ratchet wheel to said conveyor ribbons in a way corresponding to the removal of paper sheets from the apparatus.

In testimony whereof we have hereunto set our hands.

JULIUS GIESECKE.
HERMANN GIESECKE.
